FIG. 1

FIG. 2

INVENTOR.

BY ISAAC PETERSON
Henry N. Young
ATTORNEY

UNITED STATES PATENT OFFICE

106,213

DESIGN FOR A COUNTER STOOL OR SIMILAR ARTICLE

Isaac Peterson, Oakland, Calif.

Application July 23, 1937, Serial No. 70,588

Term of patent 14 years

To all whom it may concern:

Be it known that I, Isaac Peterson, a citizen of the United States and a resident of Oakland, in the county of Alameda and State of California, have invented a new, original, and ornamental Design for a Counter Stool or Similar Article, of which the following is a specification, reference being had to the accompanying drawing, forming part thereof, wherein

Figure 1 is a perspective view of the counter stool or similar article showing my design; and

I claim:

The ornamental design for a counter stool or similar article, substantially as shown.

ISAAC PETERSON.
